(21) Appl. No.: **29/400,848**

(57) **CLAIM**
The ornamental design for a molded mascara brush head with branched teeth, substantially as shown and described.

(22) Filed: **Sep. 1, 2011**

DESCRIPTION

(51) **LOC (9) Cl.** **04-02**

FIG. 1 is a top, front, left side perspective view of a molded mascara brush head with branched teeth showing our new design;

(52) **U.S. Cl.** **D4/133; D4/136**

FIG. 2 is a rear elevation view thereof with the brush head rotated to the left;

(58) **Field of Classification Search** D4/128,

FIG. 3 is a top, left side perspective view thereof with the brush head rotated to the same position as that shown in FIG. 2;

D4/133, 134, 136; 15/188, 207.2; D28/7,
D28/28, 35, 37; 132/142, 216, 218, 313,
132/317

FIG. 4 is a rear elevation view thereof;

See application file for complete search history.

FIG. 5 is a top plan view thereof;

(56) **References Cited**

FIG. 6 is a front elevation view thereof;

U.S. PATENT DOCUMENTS

FIG. 7 is a rear elevation view thereof with the brush head rotated further to the left;
